SVEN J. STRID, OF CHICAGO, ILLINOIS, ASSIGNOR OF ONE-HALF TO EDWARD CARLSON,
OF ROSELAND, CHICAGO, ILLINOIS.

DRAFT-RIGGING AND BUFFER MECHANISM.

1,219,604.

Specification of Letters Patent.

Patented Mar. 20, 1917.

Application filed August 9, 1909. Serial No. 511,942.

To all whom it may concern:

Be it known that I, SVEN J. STRID, a subject of the King of Sweden, residing at Roseland, Chicago, Cook County, Illinois, 5 have invented certain new and useful Improvements in Draft-Rigging and Buffer Mechanism, of which the following is a specification.

My invention relates to mechanism for 10 use equally in connection with draft-rigging and buffers for railway cars and the like and the object thereof is to produce a simple and efficient mechanism of this general character. Speaking in general terms, I employ a spring or series of springs and associate them with certain parts or members 15 operating in connection with the buffer angle or plate or with the draw-bar (according to the particular use) in such a manner that in the movements of the buffer angle or the draw-bar the spring or springs are acted upon in opposite directions, such 20 action taking place in the present instance through the medium of curved lever arms whose inner contour is such that the power 25 arm in the curved lever decreases according to its movement. This and also the effect caused by the friction obtained from the curved lever arms against the socket assists 30 the springs in resisting the thrust. The various features of advantage and utility in my new mechanism will be apparent from the description hereinafter given.

In the drawings, Figure 1 is a plan view 35 of my invention as applied to a draft rigging; Fig. 2 a side elevation of a portion of the structure shown in Fig. 1; Fig. 3 a detail view of the yoke coöperating with the spring; Fig. 4 an end view thereof; Fig. 5 40 a longitudinal section on line 5—5 of the structure shown in Fig. 8; Fig. 6 a cross-section on the line 6—6 of Fig. 8; Fig. 7 a detail section on line 7—7 of Fig. 5 showing the structure at the rear end of the 45 springs; Fig. 8 a plan view of a buffer construction embodying my invention; Fig. 9 a detail view of the yoke shown in Fig. 8; and Fig. 10 another detail view of the same yoke.

As hereinbefore stated, my invention is 50 applicable as well to buffers or movable

platforms as to draft rigging and I have accordingly shown both embodiments of my invention in the drawings and I will now proceed to describe both of them beginning 55 with the draft rigging construction which is illustrated in Figs. 1 to 4.

The structure shown in Fig. 1 comprises as usual an end sill 1 and the two center sills 2. Between these center sills I secure 60 two similar metallic supports 3 of irregular shape and adapted to support the spring mechanism and associated parts. These metallic supports are in practice castings and are technically called lug-castings because of the fact that they are composed of plates secured to the center sills and provided with lugs which engage or coöperate with the parts which they are to support. The usual draw-head 4 is provided with a 70 rectangular-shaped strap 5 which extends around a movable block 6 adapted to move longitudinally in said supports or lug castings 3 as hereinafter made apparent. Within said strap 5 is arranged a yoke 7 open at 75 its inner end where it projects into the block 6 and forming a spring seat or abutment at its bottom or outer end for a heavy coiled spring 8. In practice this outer end of the yoke does not bear directly against 80 the draw-bar structure but a block or follower 9 is interposed. The block 6 has at its outer end a socket portion into which the yoke 7 extends as stated and the bottom of such socket portion is provided with two 85 similar curved bearing surfaces corresponding in contour to the bearing surfaces of two similar movable levers 10 as clearly shown in Fig. 1. The outer ends of these levers are contacted and operated by the 90 inner or free ends of the yoke 7 while their inner ends bear against a follower 11 movable within the yoke and forming the inner spring-seat for the spring 8.

As a result of the foregoing construction, 95 it is evident that when the draw-bar is forced inwardly, for instance, the thrust is communicated to the yoke, thereby compressing the coiled spring and at the same time the inward movement of the yoke 100 causes a movement of the levers 10 in a direction to force the follower 11 outwardly,

that is to further compress the coiled spring, the two curved levers decreasing in their power arms with the movement of the yoke, thereby assisting the spring. At the same time the rather large bearing surface of these levers creates a friction which also aids the spring in resisting the thrust of the draw-bar. It will be understood that in this inward movement of the draw-bar the block 6 is limited as to inward movement by means of the lugs 3^a on the lug castings 3. The structure is also designed to efficiently resist the outward pull of the draw-bar or head, inasmuch as in such action the strap 5 of the draw-bar which is in contact with the block 6 will draw the latter outwardly whereupon the same general spring and friction action as before will take place. It will be particularly noted that when this block 6 is moved outwardly the levers 10 will be forced against the follower 11 to move the latter and thereby compress the coiled spring. It will be understood that in this particular action the outward movement of the yoke 25 7 and the follower 9 is limited by means of the lugs 3^b of the lug castings 3.

When my invention is applied to a buffer the same general construction is employed and the same general operation takes place. As shown in Fig. 8 the so-called buffer angle or plate 12 is pivotally connected as usual with the two side stems 13 having the usual springs 14. A center stem 15 bears at its outer end against the buffer angle, but in such a manner as not to interfere with the pivotal or tilting action thereof. The inner end of this center stem engages or co-operates with the bottom of a yoke 16 which has a sliding movement in the frame or supports 17 mounted upon the two center sills 17^a which are here of the I-beam construction. In this particular instance I employ a plurality of heavy coiled springs 18, arranged within the yoke 16 with their outer ends bearing against the bottom of the yoke and with their inner ends bearing against a follower 19. The two movable levers 20 are adapted to move in corresponding sockets in a stationary block 21 in the same manner as the levers hereinbefore described. When the buffer angle is forced inwardly, the yoke 16 is likewise moved in the same direction, with the result that the contact of the inner ends of the yoke with the levers 20 will force the inner ends of such levers against the follower 19 and thereby increase the compression of the spring caused by the inward movement of the yoke; also, the friction caused by the movement of the levers 20 will assist the springs in resisting the inward thrust of the buffer angle. By the use of my invention I am enabled to provide a comparatively simple but efficient and reliable mechanism either for buffer mechanism or for 50 55 60 65 70 75 80 85 90 95 100 105 110 115 120 125 that the spring is operated upon, that is compressed from opposite directions and at the same time the advantageous effects in the curved lever arms decreasing in their power arms simultaneously with the movement in the yoke, and also the friction in the curved levers, are obtained.

It will be understood that the yoke is freely movable within its supports as distinguished from constructions wherein friction is applied or caused during the movements thereof and therefore my yoke may be said to be frictionless. I obtain all of the buffing action or resistance through the medium of a spring or springs which are compressed initially in the coming together of the arms, for instance, by the force of such contact and subsequently by the movement of a follower in the opposite direction caused by the contact of the two arms of the yoke with the curved levers which overlap as shown and move in opposite directions to force the follower in the same direction.

I claim:

1. A device of the character described comprising a one-piece yoke which has a free rectilinear movement and which has two parallel arms, a spring arranged therein and bearing against the outer end of the yoke, and a pair of levers acted upon and moved by said arms to cause such levers to act against the spring to compress it in all pulling and buffing movements, the line and direction of the pressure being from the yoke through the levers to the spring, and the yoke and levers transmitting the entire pressure due from said movements.
2. A device of the character described comprising a one-piece yoke which has a free rectilinear movement and which has two parallel arms, a spring arranged therein and having one end bearing against the outer end of the yoke, a follower at the other end of the spring, and a pair of levers whose outer ends are acted upon and moved in unison by the arms of the yoke to cause the inner ends of the levers to bear against the follower to compress the spring in all pulling and buffing movements, the line and direction of the pressure being from the yoke through the levers, to the spring, and the yoke and levers transmitting the entire pressure due from said movements.
3. A device of the character described comprising a one-piece yoke which has a free rectilinear movement and which has two parallel arms, a spring arranged therein and having one end bearing against the outer end of the yoke, a follower at the other end of the spring, and a pair of similar curved levers acted upon at one end of said arms of the yoke and arranged at their other end to act upon the spring to compress it in all pulling and buffing movements, the line and direction of the pressure being from the yoke,

through the levers, to the spring, and the yoke and levers transmitting the entire pressure due from said movements.

4. A device of the character described comprising a one-piece yoke which has a free rectilinear movement and which has two parallel arms, a spring arranged therein and having one end bearing against the outer end of the yoke, a follower at the other end of the spring, a pair of similar curved and overlapping levers acted upon at one end by said arms of the yoke, and arranged at their other end to act upon the spring to compress it in all pulling and buffing movements, and draft beams between which said yoke has its said movements.

5. A device of the character described comprising a one-piece yoke which has a free rectilinear movement and which has two parallel arms, a spring arranged therein and having one end bearing against the outer end of the yoke, a block which is located at the open end of the yoke and which is unconnected therewith, and a pair of levers whose outer ends are acted upon and moved by the arms of the yoke and whose inner ends are arranged to act against the spring to compress it, said levers bearing against said block, the line and direction of the pressure being from the yoke through the levers to the spring, and the yoke and levers transmitting the entire pressure due from all pulling and buffing movements.

6. A device of the character described comprising a one-piece yoke which has a free rectilinear movement and which has two parallel arms, a spring arranged therein and having one end bearing against the outer end of the yoke, a block located at the open end of the yoke and having a sliding fit therein but being unconnected therewith, said block having two curved sockets and a pair of similar curved levers received by and movable in said sockets and adapted to be moved by the arms of the yoke in their movements to cause compression of the spring.

7. A device of the character described comprising a one-piece yoke which has a free rectilinear movement and which has two parallel arms, a spring arranged therein and having one end bearing against the outer end of the yoke, a block located at the open end of the yoke and having a sliding fit therein but unconnected therewith, said block having two curved sockets, a follower at the other end of the spring, a pair of levers interposed between the block and spring and arranged to be contacted and operated by the arms of the yoke, and a follower 9 against which the outer end of said yoke bears.

8. A device of the character described comprising a one-piece yoke which has a free rectilinear movement and which has two parallel arms, a spring arranged therein and having one end bearing against the

outer end of the yoke, a supporting member for the yoke, a block movable between such members and at the open end of the yoke and being unconnected with such yoke, a follower arranged within the yoke and co-operating with the spring, a second follower 9 which is arranged between said members and against which the outer end of the yoke bears, and a pair of levers interposed between the block and follower 19 and adapted to move in opposite directions and in unison upon such follower, the line and direction of the pressure being from the yoke, through the levers, to the spring, and the yoke and levers transmitting the entire pressure due from pulling and buffing movements.

9. A device of the character described comprising a one-piece yoke which has a free rectilinear movement and which has two parallel arms, a spring arranged therein and having one end bearing against the outer end of the yoke, draft beams between which the yoke is located, a block 6 movable longitudinally between the beams and having an outwardly projecting tubular portion, said yoke having a sliding fit in said tubular portion but being unconnected therewith, a pair of correspondingly curved overlapping levers arranged within the block and interposed between the arms of the yoke and the spring, and a follower 9 which is movable between the beams and against which the yoke bears at its outer end.

10. In combination with a draw bar and a strap at the inner end thereof, a frictionless yoke movable with the draw bar, a spring therein, a block movable with the strap in one direction and levers interposed between the block and spring and operated in unison to compress the spring to resist the buffing action when contacted by the arms of the yoke, the line and direction of the pressure being from the yoke through the levers to the spring.

11. In combination with a draw-bar and a strap at the inner end thereof, a one-piece yoke 7 having parallel arms, a spring 8 therein, a follower 9 against which the yoke bears at its outer end, a block 6 in which said arms freely slide, a follower 11 freely movable within the yoke and co-operating with the spring, and a pair of curved levers 10 interposed between the block and follower, the line and direction of the pressure being from the yoke through the levers and follower to the spring and the yoke and levers transmitting the entire pressure due from pulling or buffing movements to the spring.

12. A device of the character described comprising a movable yoke, a spring therein, and two levers having overlapping ends and acted upon by opposite sides of the yoke

- in its movements and arranged to act upon the spring to compress the same to resist buffing action, said levers being arranged to move from different points but in substantially the same direction at their overlapping ends against and longitudinally of the spring, and said levers being curved to cause an increase in their leverage upon the spring as the yoke continues to move with the buffing force.
13. A device of the character described comprising a movable yoke, a spring therein, a follower at one end of the spring and two levers having overlapping ends and acted upon by opposite sides of the yoke in its movements and arranged to act upon the spring to compress the same to resist buffing action, said levers being arranged to move from different points but in substantially the same direction at their overlapping ends against the follower and longitudinally of the spring, and said levers being curved to cause an increase in their leverage upon the spring as the yoke continues to move with the buffing force.
14. A device of the character described comprising a movable yoke, a spring therein, levers acted upon by the yoke in its movements, a follower interposed between the levers and the spring, and a block having curved sockets, said levers being correspondingly curved and having ends overlapping and movable against the follower.
15. A device of the character described comprising a movable yoke, a spring therein, levers acted upon by the yoke in its movements, a follower interposed between the levers and the spring, and a block having socket bearings for the levers, such levers having ends overlapping and movable against the follower.
16. In a friction draft rigging, a member having a friction surface, a segmental friction element having a rotative friction engagement with such surface, a longitudinally movable follower member in contact with one end of such element, and another longitudinally movable follower member in contact with the other end of the element; substantially as described.
17. In a friction draft rigging, a member having arcuate friction surfaces, a plurality of friction elements having coacting friction surfaces, a front follower arranged to engage one end of each of said elements, and an inner follower having engagement with the opposite ends of said elements, together with springs seating against the inner follower and the front follower; substantially as described.
18. In frictional shock-absorbing mechanism, an arcuate friction element rotatable about a single axis; a plurality of followers; and a spring, the spring being arranged longitudinally of the mechanism, said friction element being engaged at both its ends by longitudinally movable followers and frictionally engaged intermediate its ends by another follower.
19. In frictional shock-absorbing mechanism, an arcuate friction element rotatable about a single axis; a plurality of followers; and a spring, said friction element being engaged at both its ends by longitudinally movable followers and frictionally engaged intermediate its ends by a socket bearing on another follower, said socket being curved to the arc of a circle whose center is coincident with the axis of rotation of said friction element.
20. In friction shock-absorbing mechanism, an arcuate friction element; a plurality of followers; and a spring, said friction element being adapted to rotate in a frictional socket bearing in one of said followers and being engaged at both its ends by other followers, all of said followers being longitudinally movable to cause said friction element to rotate in its socket.
21. In a friction draft rigging, a follower having a curved socket portion, a rotative friction element seated in said socket portion, a second follower, arranged to be moved in an opposite direction from the first follower, engaging one end of said friction element, an inner follower engaging the other end of said friction element, and a spring interposed between the first named follower and the inner follower; substantially as described.
22. In a draft rigging, spring mechanism, loosely mounted levers at one end thereof, the levers being adapted to bear upon said spring mechanism, a follower at the other end of the spring mechanism and an extension stationary with relation to the follower and adapted to form a fulcrum connection between the latter and one end of the levers.
23. In a draft rigging, spring mechanism, loosely mounted levers at one end thereof, the levers being adapted to bear upon said spring mechanism, a follower at the other end of the spring mechanism and an extension stationary with relation to the follower and adapted to form a fulcrum connection between the latter and one end of the levers, such levers being normally out of engagement with their fulcrum connection.
24. A draft rigging for cars comprising an elongated member having one end open, levers arranged adjacent to the open end of said member and normally out of engagement therewith, and spring mechanism located within said member and arranged to exert pressure on said levers, the member and levers being arranged to project beyond the line of the draw bar.
25. A draft rigging for cars comprising cheek plates provided with draft lugs at both ends thereof, a hollow member, levers

arranged at one end of said member and yieldingly held out of positive engagement therewith, coacting surfaces whereby movement of the levers lengthwise of one another is prevented, and a draw-bar extension arranged about said member and levers whereby they are moved in a longitudinal direc-

tion so that the force applied by the draw-bar will be in a line substantially parallel with the sides of the car.
